JOHN J. MARCY, OF MERIDEN, CONNECTICUT, ASSIGNOR TO HIMSELF
AND E. MILLER & CO., OF SAME PLACE.

Letters Patent No. 100,912, dated March 15, 1870.

IMPROVEMENT IN MACHINE FOR SPINNING SHEET METAL.

The Schedule referred to in these Letters Patent and making part of the same.

To all whom it may concern:

Be it known that I, JOHN J. MARCY, of Meriden, in the county of New Haven, and State of Connecticut, have invented a new Improvement in Machine for Spinning Metal; and I do hereby declare the following, when taken in connection with the accompanying drawings and the letters of reference marked thereon, to be a full, clear, and exact description of the same, and which said drawings constitute part of this specification, and represent in—

Figure 1, a top view;

Figure 2, a front-side view;

Figure 3, a right-hand end view;

Figure 4, a top view, with the parts in different positions, to illustrate the operation of the invention; and in

Figures 5, 6, and 7, detached views.

This invention relates to an improvement in the machine patented to me, April 27, 1869, for spinning metal, that is to say, the working of metal into shape upon a former, by causing the former and disk to revolve rapidly, and a suitable instrument pressed against the disk to work or draw the metal down onto the former. This is the usual method for spinning, and is employed for the making of hollow vessels and articles of various character.

In my aforesaid patent, the tool is guided by a fixed form. Any change from that form requires the removal of the form and the substitution of another. By my improvement I combine adjustable guides, whereby the adjustment is made without such removal or substitution of parts; and

My invention consists in the arrangement in a spinning-machine of an adjustable guide, whereby the longitudinal movement of the spinning-tool may be adjusted; also, in the arrangement of an adjustable guide, whereby the transverse movement of the tool may be adjusted.

A is the bed of the machine, upon which, in suitable bearings B, a mandrel, B', is placed, and caused to revolve by the application of power thereto through the pulley B², in the usual manner, and to which the former D is fixed, so as to revolve with the said mandrel. The said former is wrought in the shape required for the article to be produced.

C is a mandrel having a longitudinal movement, that is, arranged so as to move axially to or from the center of the former, so that when the disk of metal is placed against the former it may be firmly held in position by pressing the mandrel C firmly against it, as in common spinning-machines where the tool is guided by hand, and also as shown in my patent before referred to.

F is a slide arranged so as to work transversely across the bed in a guide, E', and the said guide E' arranged so as to move longitudinally on the bed of

the machine. On the said slide the spinning-tool F is arranged, held in any convenient manner, and may be in like manner as the tool of a "slide-rest."

G is a plate, by preference of a circular form, arranged so as to turn on a table, H, to any desired position around a center.

In order to permit the turning of the plate G upon the table, the plate is constructed upon the under side, as seen in fig. 7, with a circular T-shaped slot, d, with T-headed bolts e extending down through the table H, with nuts h, so that by the loosening of the nuts the plate G may be turned to any desired position.

On the plate G a slide, I, is arranged, so as to move freely thereon. From the said slide I a rod, I¹, extends, and is pivoted at f to an adjustable arm, I², on the guide E', and is also pivoted at n on the slide E.

I will first describe the operation of the slide I, as shown in figs. 1, 2, and 3. To the guide E' a longitudinal reciprocating movement is imparted by an adjustable crank-wheel, L, through a lever, L², and rod L¹, the said crank-wheel being turned in the operation by means of the handle L³ or other suitable device. With the plate G set so that the slide I will move therein at an angle relatively to the machine, as in fig. 1, and the movement imparted to the slide E by the crank, as before described, there will be given to the slide, in combination with such direct reciprocating movement, a transverse movement corresponding to the angle or path of movement of the slide I, the slide I being connected directly to the guide E' and also to the slide E, the slide I will be drawn with the guide E', and, at the same time, by means of the connection n, the slide E will be drawn out, thus imparting to the tool F a movement corresponding to the incline of the former D. This movement is denoted by the broken lines, fig. 1.

It will be evident that the angle of the movement of the tool may be adjusted by turning the plate G', and also that the reciprocating movement may be adjusted by means of the crank L, the adjustment of the crank being the common adjustment.

To change the position of the tool or of the connections, I make the arm I² adjustable, as seen in fig. 1, so as to throw the pivot f out or in, as the case may be, and also arrange the table H upon a slide, H', so that it may be moved out or in, as the case may be; and also, as seen in fig. 2, arrange the slide H', by means of a longitudinal guide, t, so that it may be moved longitudinally on the bed of the machine.

To accommodate the tool to any slight irregularity of the surface, I form the table G with a top plate, G, a recess being formed in the plate G, and a spring, T, arranged therein, so as to bear against a stud, T', on the plate b, so that the tendency of the said spring is to hold the top plate G' in one position, the said plate G' being arranged with slots a as guides. When the

said plate G' is turned against the spring with sufficient force, the spring will yield; hence, any slight irregularity on the surface of the former would tend to throw out the tool, which, bearing against the slide I on the plate G', will also tend to turn the said plate G' against the spring, by this means affording a yielding pressure of the tool against the work.

If, in working, it is at any time desirable to throw the tool out from the work, as, for instance, when the tool is returning after passing over the surface, I arrange a cam, W, under the plate G', so as to bear against the stud W¹ on the plate G, the said cam being turned by a handle or wheel, W², (see figs. 1 and 2,) and bearing against the said stud turns the plate, with the slide I, so as to change the angle sufficiently to draw the tool slightly away from the former, and the tool is returned to its proper position by releasing or returning the cam.

N is a crank-wheel, arranged upon a vertical shaft, in a bearing, N', in the rear of the machine, to which a rotary movement is imparted from a crank, N², on the front of the machine, the shaft from the said crank extending through and communicating to the shaft of the crank-wheel N by means of bevel-gears N³, as seen in fig. 1.

The said crank-wheel is provided with a slot, M, upon its surface, in which a crank-pin, m, is arranged, so as to be adjustable in the said slot in the usual manner for adjustable crank-pins, and from the said crank-pin a rod, P, extends forward, and connects to the rod I¹, or may be to the slide E, if preferred.

The operation of this arrangement is shown in fig. 4. Supposing it is desired that the tool F move across the end or face of the former, say starting from the position denoted in fig. 4, the plate G is turned to give

the requisite angle of movement, and the crank N detached. Then the operator, taking the crank N², turns the wheel N, which forces the slide E out and in the direction indicated by the broken lines.

It should be here remarked, that when the crank L is attached as first described, the crank N should be detached or set, so that the longitudinal movement will not be interfered with, that is, it may be set, as in fig. 1, and the crank will partially rotate by the movement of the slide E.

I claim as my invention—

1. In combination with the tool-carrying slide E, the plate G, made adjustable to vary the angle of and carry the slide I, substantially as herein set forth.
2. The plate G, when constructed in two parts, G and G', and arranged with a spring, T, between the two, so as to afford a yielding pressure to the tool, substantially as set forth.
3. In combination with the subject-matter of the second clause of claim, the cam W and stud W¹, constructed and operating as described.
4. In combination with the slide E, the arrangement of the arm I² and plate G, so as to be adjusted transversely on the machine to adjust the position of the tool, as set forth.
5. In combination with the tool-carrying slide E, the adjustable crank N, so as to impart a transverse movement to the slide E.
6. In combination with the tool-carrying slide E and adjustable plate G, with its slide I, the adjustable crank N, operating together as specified.

JOHN J. MARCY.
